PROCESS FOR DEWAXING OIL

David R. Merrill, Long Beach, and Philip Subkow, Los Angeles, Calif., assignors to Union Oil Company of California, Los Angeles, Calif., a corporation of California

Application October 24, 1932, Serial No. 639,340

11 Claims. (Cl. 196—18)

This invention relates to a process for the separation from petroleum of those hydrocarbons which are normally solid at ordinary temperatures. According to our process we are able to separate from petroleum or mineral oil such substances as asphalt, paraffin, crystalline or amorphous wax, or gummy or resinous substances which may be present. While our invention is particularly adapted to the removal of paraffin, amorphous or crystalline wax, or gummy or resinous substances from lubricating oil, it may be utilized in the treatment of any other petroleum fraction where it is desirable to separate the oil from the foregoing substances.

Many crude oils from which lubricating oil is produced contain paraffin or wax. It is found associated with the lubricating oil fractions of paraffin base crude oil and with the lubricating oil fractions produced from any of the mixed base and asphalt base crude oils. It is not only of doubtful lubricating value but also limits the temperature at which lubricants containing it may be used by congealing at the lower temperatures. Therefore, in the production of lubricating oils from petroleum fractions containing wax or paraffin, it is customary to remove a substantial portion of the wax or paraffin present in the oil in order to lower the temperature at which the final product congeals. The temperature at which an oil congeals is commonly referred to as its "pour point" and this value is usually obtained according to method D—97—30 of the American Society of Testing Materials.

Several methods well known in the art are employed at present for the production of low "pour point" lubricating oil stock from petroleum fractions which contain substances congealing at high temperatures as set forth above and to which we shall hereinafter refer as wax. In the cold settling process, the wax-containing oil is first diluted with a light hydrocarbon diluent, such as naphtha, gasoline or kerosene. The diluted oil and wax are then run into a tank of large capacity and slowly chilled by the aid of brine circulated in coils located within the tank. The chilling process is carried out for a period of from 20 to 50 hours until a temperature is reached at which there exists a substantial separation of the wax in the form of a slime or gel from the solution of oil. By allowing the cold solution of oil containing precipitated wax to stand for a period of several days the precipitated wax settles to the bottom of the settling tank. While this method has been used extensively for the separation of wax from lubricating oil, it is

objectionable because of the cost of refrigerating the diluted oil over so long a period, furthermore, because of the large tank and refrigerating capacity required for the treatment of the oil and lastly on account of the usual poor separation obtained between the wax and the oil.

Another method for dewaxing petroleum which has been used to a large extent is the cold pressing process. Wax distillate produced from those fractions of petroleum distilling over between the approximate temperature limits of 450° F. and 725° F. is slowly chilled to a temperature of about 15° F. to 30° F. whereupon the wax present in the oil precipitates to form a product having a mushy consistency. The cold, mushy mass is then pumped through a filter press under a pressure of 300 to 350 pounds per square inch. The wax present is collected upon the filter and the oil is recovered as a pressed distillate relatively free from wax. When the oil under treatment contains a relatively large quantity of wax it is sometimes necessary to re-chill and re-filter it in order to obtain an oil having the desired pour point. The length of time required to filter the chilled oil depends upon the crystalline structure of the wax. A distillate which is poorly crystallized, i. e., with crystals in the form of plates, or in which the wax crystals are small, requires a much longer period of filtration than does a distillate in which the wax crystals are large and of needle structure. This process has found commercial application only in conjunction with oils having the wax present in a crystalline form, as so-called amorphous wax or micro-crystalline wax is extremely difficult to separate by filtration from the oil. Consequently, oils containing amorphous wax cannot be treated on a commercial scale by this process.

Another process has been suggested which consists in diluting the oil containing wax with such light petroleum hydrocarbons as gasoline, naphtha or kerosene, adding to the diluted oil a wax-adherent material, chilling the mixture of oil and wax-adherent material with constant agitation until a temperature is reached which is sufficiently low to cause the wax present in the oil to precipitate and collect upon the wax-adherent material and finally separating the substantially wax-free oil by filtration from the wax-adherent material and wax. Again this process is objectionable because of the long period of time required to obtain suitable wax separation from the diluted oil and also because of the large chilling and filtering capacity required to make the process commercially possible.

It has been found that many of the disadvantages present in the foregoing processes may be overcome by removing the waxy constituents of petroleum in the presence of light hydrocarbons, 5 such as propane.

The liquid propane lowers the viscosity of the chilled mass sufficiently to facilitate the separation of the precipitated wax from the chilled solution of propane and oil.

10 We have found that waxes which have been precipitated from gasoline or naphtha by chilling a light waxy oil dissolved in these solvents are usually highly amorphous in structure. Likewise, we have found that when wax-containing 15 oil is rapidly chilled in the presence of propane, the wax precipitates in so fine a form of subdivision that filtering or settling is substantially impeded. Such waxes are in the nature of gels 20 or slimes and as such offer many difficulties in their removal from the chilled solution of oil and solvent. As already discussed, they are unusually hard to separate by ordinary filtration methods as the slimy wax forms an impervious layer upon the filter plate of the filter press which obstructs 25 free movement of the dewaxed oil through the filter plate and filtration is usually possible only if excessive amounts of filter aid are employed. Furthermore, the wax flocks or aggregations which are formed during the chilling operation 30 will not readily settle out by cold settling methods even in the presence of propane which increases the difference in the specific gravity between the solution of oil in the solvent and the wax.

We have discovered that the precipitation of 35 the wax in the presence of propane into a form too finely divided for efficient settling and/or filtration is caused by a too rapid cooling of the solution of oil, wax and propane. This rapid cooling we call "shock chilling." We have invented a process whereby shock chilling is prevented, the oil, wax and propane solution being cooled in successive stages while sufficient time 40 is allowed to permit the wax crystals to re-crystallize and grow, the crystals formed in an earlier stage forming nuclei for the further development of crystals in the later stages of crystal 45 formation.

Due to the granular structure which the wax 50 possesses when precipitated from a chilled propane solution of waxy oil in this manner, it may be separated commercially from the propane solution of oil by filtration or settling with none of the attending difficulties present when filtering or settling waxy slimes. When filtering, the 55 granular structure of the wax does not form the impervious film over the filter plate which is characteristic of waxy slimes or gels. Instead, such granular waxes form a porous layer upon the filter plate through which the wax-free oil dissolved in solvent may freely flow. When settling, the long period necessary to obtain separation of the precipitated wax is obviated.

Another advantage of using a light liquid hydrocarbon as a diluent for the oil containing wax 60 is that by allowing a portion of the solvent to vaporize under reduced pressure, the necessary refrigeration is obtained to chill the oil to the desired dewaxing temperature. The waxy oil is first dissolved under pressure in a light liquid hydrocarbon. A portion of the light liquid hydrocarbon is vaporized or allowed to boil off at reduced pressure which thereby lowers the temperature of the waxy oil dissolved in the remaining solvent to a point sufficiently low to 70 precipitate the wax. Thus, the light liquid hydro-

carbon functions as a diluent for the wax-bearing oil and also as an internal refrigerant to chill the solution of oil and wax to the proper dewaxing temperature. Furthermore, this internal refrigeration may occur in the propane itself 5 prior to intermixture with the oil and wax.

When we use the term "light liquid hydrocarbon", we mean those hydrocarbons which are normally in the vapor state at atmospheric pressure and temperature. Such hydrocarbons include propane, isobutane, butane, ethane, methane and mixtures thereof. These may be obtained by the rectification of casinghead gasoline by the so-called "stabilizing method". They are the overhead thus obtained. They are liquefied by compression and cooling in the conventional manner and are drawn off into pressure chambers where they are maintained in a liquid state until they are used. For example, a fraction composed of 6.72% ethane, 72.2% propane, 10 19.91% isobutane and 1.17% normal butane is satisfactory. It will be understood, however, that this merely illustrates the type of fractions which may be used and that the composition may vary. This fraction will hereafter be referred to as "propane" for purposes of simplicity.

It is an object of our invention to precipitate granular wax from wax-bearing oil and separate said wax from said oil.

It is another object of our invention to precipitate wax in granular form from wax-bearing oil by the use of liquid propane and subsequently to separate the wax, oil and propane from each other.

Another object is to chill the wax-bearing oil 35 in stages by the successive introduction of propane into said oil whereby granular wax precipitates from the solution.

A further object is to chill the wax bearing oil in stages thereby permitting crystal growth in 40 order to avoid the production of amorphous wax or wax gels or slimes.

An additional object is to so control the time and degree of chilling that crystal growth is aided and granular wax is produced.

In the drawing, Fig. 1 is one form of apparatus which we may employ to carry out our process. Fig. 2 is a cross sectional view of the expansion valve 54 which we prefer to use in chamber 55. Fig. 3 is a cross section of an orifice mixer which 50 we may employ to produce an intimate mixture between two liquids.

Referring more particularly to Fig. 1, propane in liquid form is held under pressure in tank 10 and waxy oil is contained in tank 11. The waxy oil is removed therefrom by pump 12 via line 13 controlled by valve 14 and is passed through orifice mixers 15, 16 and 17 into crystallizer tank 20. During flow of the waxy oil through line 13 and the orifice mixers, liquid propane is introduced into the oil through lines 24, 27 and 50 in the manner described below. Preferably the liquid propane is introduced at successively lower temperatures. The orifice mixer of Fig. 3 may be any one of the mixers 15, 16, 17. The fluids in 65 pipe 13 pass successively through diaphragms 6 which are provided with openings 7. After leaving the constricted openings 7, the fluid passes into chambers 8. The successive passage of the liquids through the diaphragms into the enlarged 70 chambers 8 produces sufficient intermixture to insure intimate contact of these fluids.

Liquid propane from storage 10 issues therefrom by action of pump 21 via line 22 controlled by valve 23. The flow of liquid propane is then split, 75

part passing via line 24 controlled by valve 25 to join with the waxy oil traveling through line 13 prior to passage into orifice mixer 15 while the remainder of the liquid propane passes 5 through line 26 in heat interchange with the material passing through line 117 described below. From line 26, the stream of liquid propane is again split, part passing via line 27 controlled by valve 28 to line 13 at a point intermediate orifice mixers 15 and 16 while the remaining liquid propane passes via line 29 into evaporator 30. The flow through line 29 is regulated by float controlled valve 35 operated in the usual manner by the amount of liquid maintained in evaporator 30. 10 15 The pressure in the evaporator is reduced sufficiently to partially vaporize the propane contained therein.

Propane vapors in tank 30 are removed therefrom through line 36 controlled by valve 37 and 20 25 through line 38 by action of pump 39. These vapors are compressed in compressor 40 in line 41 connected with line 38 and after condensation in condenser 42 the liquid propane is passed via line 43 to propane storage 10.

25 The chilled propane which remains liquid in evaporator 30 passes therefrom by action of pump 47 via line 48 controlled by valve 49. This stream of liquid propane may then be split, part passing via line 50 controlled by valve 51 to intermix with 30 the waxy oil flowing through line 13 at a point intermediate orifice mixers 16 and 17 and part passing through line 100 for use in the manner described below.

35 Thus, the propane in liquid state is introduced in successive stages into the stream of wax-bearing oil, and the propane introduced in each successive stage is at a lower temperature than that added to the oil in the preceding stage. Sudden local excessive chilling is thus avoided, i. e. shock chilling is thereby prevented by a gradual reduction of temperature and the resultant precipitated wax tends to be in granular form whereas shock chilling produces gel-like wax which is 40 difficultly separable by settling or filtration, as 45 stated above.

We have found that the production of wax in granular form is aided by allowing the propane to contact with the wax bearing oil for a sufficient time after intermixture therewith. Consequently, we have provided crystallizer chamber 20 in which the oil, wax and propane flow in intimate contact for the time necessary to cause crystal growth and recrystallization. The evil effects of shock chilling and the production of amorphous wax are thereby substantially avoided. The mixture of oil, wax and liquid propane in tank 20 is withdrawn therefrom by pump 52 in line 55 50 55 60 65 70 75 80 85 90 95 100 105 110 115 120 125 130 135 140 145 150 155 160 165 170 175 180 185 inating in tower 125 pass therefrom via line 128 controlled by valve 129 into condenser 130 and thence via line 133 into liquid vapor separator 134. Uncondensed propane issues therefrom by action of pump 137 via line 135 controlled by valve 136. Line 135 connects with line 41 and the propane is condensed in the manner described above.

Condensed propane in separator 134 passes therefrom via line 138 controlled by valve 139 by action of pump 140. The stream may then be split, part passing into propane storage 10 via line 141 controlled by valve 142 and via line 43. Another part may pass into still 125 via line 143 controlled by valve 144 for use as a refluxing medium.

Unvaporized dewaxed oil issues from still 125 via line 145 and valve 146 by action of pump 147. This stream may be split, part returning via line 148 controlled by valve 149 into the still 125 as a reflux medium while the other portion travels via line 150 controlled by valve 151 through line 152 into heat exchange with the dewaxed oil flowing through line 119. From 152 the unvaporized dewaxed oil flows through line 153 into de-waxed oil storage tank 155.

As illustrative of the operation of our process for one type of oil and without intending to limit our invention, the oil in tank 11 may be a lubricating oil containing wax. It is maintained therein above the wax congealing temperature. Part of the propane from storage 10 at about 60° F. intermingles with the oil in mixer 15 after passage through valve 25. If necessary, the oil and/or propane may be heated in order to accomplish complete solution of the oil and wax in the propane prior to wax separation.

Another portion of the propane is chilled in line 26 before introduction into the waxy oil via valve 28. If the cooling in 26 by heat exchange with dewaxed oil in 117 is not sufficient, additional cooling, not shown, before passage through valve 28 may be provided. The temperature in 16 is for example, about 20° F. to 30° F. The third portion of propane, subjected to partial evaporation in evaporator 30, is preferably at a still lower temperature. If desired, the vaporization in 30 may take place under vacuum whereby extremely low temperatures will prevail in the remaining liquid propane. The temperature in mixer 17 and tank 20 may be approximately 5° F. to -5° F.

In insulated crystallizer tank 20, which is of larger cross-sectional area and larger volume than line 13 the rate of flow of oil and precipitated wax is substantially reduced whereby the wax is given sufficient time to crystallize, recrystallize and grow into the desired form. Final refrigeration occurs in chamber 55 by expansion through valve 54 and vaporization of the propane. The temperature in 55 may be -10° F. to -20° F. although -40° F. or lower can sometimes be advantageously employed. The temperature can be varied by employing appropriate pressures or vacuum depending upon the cold test desired for the oil obtained as a final product.

By these gradual, successive reductions in temperature and by giving the wax ample time to crystallize, an easily separable, granular wax is produced. Chamber 55 may also be sufficiently large to provide additional time for crystallization during flow of the mixture therethrough. However, it is also desired to provide an additional chamber to act as a settling tank. The oil, wax and liquid propane in 55 exiting via line 78 is pumped into settling chamber 80 where settling

of the wax takes place and additional time for crystallization is provided. Due to the low viscosity of the propane solution and the wide difference in the gravity of the wax and the gravity of the propane solution of oil and due to the granular nature of the wax crystals, the latter tend to settle rapidly to the bottom of settling tank 80 leaving a clear layer at the top.

The temperature in 80 should approximate that in 55. Preferably, we desire to prevent vaporization in settling chamber 80 because of the turbulence produced thereby. Stratification has been found to take place more readily in a quiescent state. Accordingly, settling chamber 80 should be maintained at the same pressure as vaporizer 55; or if desired, a higher pressure may be employed in 80 by re-pressuring with gaseous propane or other gas to prevent boiling and avoid interference with settling. If it is desired to discharge any propane from 80 this may be accomplished via valve 81 in line 38.

In order to provide additional nuclei for the precipitation of wax crystals in 55 and permit additional time and opportunity for the recrystallization of the wax precipitated in 80, provision is made for the return of a portion of the wax precipitated in 80 to the crystallizer 55. This may be accomplished in either or both of two ways. By operating valves 85, 87, 89, 92 and 94, wax crystals as a slurry may be returned either by the jetting action of the expanding propane and oil solution through venturi 70 or by the pump 88 or by both.

A portion of the wax slurry is sent through either filter press 95 or 96 by operation of the valves 92 and 94. Assuming press 95 has been filled with wax cake, valves 104 and 92 are closed and valve 94 is opened to permit the wax, oil and propane mixture to pass through filter press 96. The filtrate leaving the filter press via line 107 and valve 108 commingles with the supernatant oil from 80 passing valves 115 and lines 114 and 116 to line 110. This mixture is forced by pump 111 into heat exchange in line 117 with the propane in line 26, then into heat exchange in line 119 with hot oil passing through line 152. The heated mixture then flows through line 120 into still 125.

While oil is being filtered through press 96, the wax caked on the plates of filter 95 is washed with cold propane coming through lines 100 and 101 and valve 102. The cold propane dissolves oil remaining in the wax cakes and this solution of oil in propane is passed via line 105 and valve 106 to commingle, if desired, in line 110 with the filtrate from filter press 96 and with the supernatant oil from settling chamber 80 entering line 110 via line 116.

While filter press 96 is operating and after the wax cakes in press 95 have been washed with the cold propane, the press 95 may be cleaned of wax in any manner desired. When press 95 is ready for operation and 96 has become filled with wax, valves 94 and 102 are closed and valve 92 is opened, permitting flow of the waxy oil and propane mixture into press 95. Valve 104 may be opened to permit the wax cakes in press 96 to be washed free of oil with cold propane. This oil and propane solution passes to line 110 via line 107 and valve 108 to commingle with the filtrate from press 95 entering line 110 via line 105 and valve 106.

The preheated oil and propane solution in line 120 is introduced into column still 125 which may be operated at high or low pressure. If the pres-

sure is to be high so that the propane may be condensed by ordinary cooling water, an additional high pressure pump 121 may be provided in line 120. The column is additionally heated by steam passing through coil 126.

Part of the condensate in 134 produced from the vapors leaving column still 125 via line 128 and condenser 130, is forced by pump 140 as reflux to still 125 via line 144 and the rest is returned via line 141 to propane storage 10. The uncondensed vapors pass via line 135 and pump 137 to compressor 40 and cooler 42 and thence to storage 10. The vapors from 55, 80 and 30 are first compressed by compressor 39 in line 38 and then are finally compressed in 40 and passed to storage, as described above. The stripped de-waxed oil is withdrawn by pump 147 and part is recirculated via valve 149 and line 148 to the column still, while part passes through 152 in heat exchange with the incoming material passing through 119. The desired stripped and de-waxed lubricating oil is stored in storage 155.

The foregoing exemplary description is merely illustrative of a preferred mode of carrying out our invention and is not to be taken as limiting, as many variations may be made within the scope of the following claims by a person skilled in the art without departing from the spirit thereof.

In our divisional application, Serial Number 34,664, filed August 5, 1935 we claim the recirculation of the separated wax to the chilling zone.

We claim:

1. A process for the separation of wax from oil containing wax which comprises precipitating said wax during the flow of said oil through a line of relatively small cross-sectional area and introducing a liquefied normally gaseous hydrocarbon at successively lower temperatures in stages at successive points along said flow of wax and oil to avoid shock chilling the wax.

2. A process for the separation of wax from oil containing wax which comprises precipitating said wax during the flow of said oil through a line of relatively small cross-sectional area and introducing liquid propane at successively lower temperatures in stages at successive points along said flow of wax and oil to avoid shock chilling the wax.

3. A process for the separation of wax from oil containing wax which comprises mixing said waxy oil with liquid propane, precipitating wax therefrom during flow of said oil, wax and propane through a line of relatively small cross-sectional area and introducing further quantities of liquid propane in stages at successive points along said flow of wax, propane and oil at successively lower temperatures to avoid shock chilling the wax.

4. A process for the separation of wax from oil containing wax which comprises commingling said waxy oil with liquid propane under pressure, precipitating said wax during flow of said oil and propane under pressure through a line of relatively small cross-sectional area and introducing further quantities of liquid propane under pressure in stages at successive points along said flow of wax, oil and propane at successively lower temperatures to avoid shock chilling the wax.

5. A method of chilling a wax-containing oil which comprises mixing said oil with a liquefied normally gaseous hydrocarbon, flowing said mixture from the initial mixing zone to a final zone of chilling, maintaining said mixture in a confined stream and without removal of vapor from said stream during said flow, and introducing

chilled liquefied normally gaseous hydrocarbon diluent into said flowing stream between the initial mixing zone and the final zone of chilling, said introduction of chilled diluent being in an amount regulated to avoid shock chilling the wax. 5

6. A process for the separation of wax from oil containing wax which comprises introducing a liquid normally vaporous hydrocarbon into said wax bearing oil, subjecting said mixture of wax, oil and hydrocarbon to pressure sufficient to maintain said hydrocarbon liquid, flowing said mixture through a constricted line in a confined stream and successively through a plurality of constricted openings in said line, introducing a further quantity of liquid normally vaporous hydrocarbon into said flowing mixture at a lower temperature at a point intermediate said plurality of constricted openings and thereafter reducing the pressure on said mixture in an expansion zone to vaporize the liquid normally vaporous hydrocarbon, chill the oil and precipitate the wax. 10

7. A process for the separation of wax from oil containing wax which comprises precipitating wax during flow of said oil through a line of relatively small cross sectional area and introducing liquid normally vaporous hydrocarbon under pressure at successively lower temperatures in stages at successive points along said flow of oil and wax, subsequently reducing the pressure on said partially cooled mixture of oil, wax and hydrocarbon in a pressure reducing zone to vaporize the liquid normally vaporous hydrocarbon, further chill the oil and precipitate the wax without shock chilling and separating said precipitated wax from said oil and liquid normally vaporous 30 hydrocarbon. 35

8. A process for the separation of wax from oil containing wax which comprises introducing liquid propane into said wax bearing oil, subjecting said mixture of wax, oil and propane to pressure sufficient to maintain the propane liquid, flowing said mixture through a constricted line in a confined stream and successively through a plurality of constricted openings in said line, introducing a further quantity of liquid propane into said flowing mixture at a lower temperature at a point intermediate said plurality of successive constricted openings and thereafter reducing the pressure on said mixture in an expansion zone to vaporize the propane, chill the oil and precipitate the wax. 50

9. A process for the separation of wax from oil containing wax which comprises precipitating wax during flow of said oil through a line of relatively small cross-sectional area and introducing liquid propane under pressure at successively lower temperatures, in stages at successive points along said flow of wax and oil, subsequently reducing the pressure on said partially cooled mixture of oil, wax and propane in a pressure reducing zone to vaporize the propane, further chill the oil and precipitate the wax without shock chilling and separating said precipitated wax from said oil and propane. 55

10. A process for dewaxing oil which comprises commingling wax containing oil and propane at temperature and pressure sufficient to maintain said propane liquid, passing said mixture in a flowing stream to a zone of final wax crystallization and introducing additional liquid propane at a lower temperature than said mixture into said propane and oil mixture at an intermediate point during said flow from the point of said first mentioned propane intermixture to said zone of final wax crystallization said introduction of chilled 70 wax crystallization said introduction of chilled 75

propane being in an amount regulated to avoid shock chilling the wax.

11. A process for dewaxing oil which comprises commingling wax containing oil and propane at a temperature and pressure sufficient to maintain said propane liquid, passing said mixture in a flowing stream to a zone of final wax crystallization and then to a zone of wax separation, and introducing additional liquid propane at a lower

temperature into said propane and oil mixture at an intermediate point during said flow from the point of said first mentioned propane intermixture to said zone of final wax crystallization said introduction of chilled propane being in an amount regulated to avoid shock chilling the wax. 5
